UNITED STATES PATENT OFFICE.

ADAM C. KRICK, OF NEWARK, NEW JERSEY.

TRAVELING-BAG.

SPECIFICATION forming part of Letters Patent No. 504,840, dated September 12, 1893.

Application filed March 28, 1893. Serial No. 467,929. (No model.)

To all whom it may concern:

Be it known that I, ADAM C. KRICK, a citizen of the United States, residing at Newark, in the county of Essex and State of New Jersey, have invented certain new and useful Improvements in Traveling-Bags, Satchels, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The present invention relates to traveling bags, satchels, &c., and consists, first, in the construction and method of securing within the bag, a toilet or sample case; secondly, of such toilet or sample case detachably arranged within the bag; thirdly, of the improved form of bag frame, whereby the bag or satchel is adapted to receive the toilet or sample case, and lastly, of securing to the lower ends of the bag frame where they are jointed or pivoted together, a device for protecting said parts of the frame and also for more firmly securing the parts of the frame together. The invention is therefore designed to provide a strong and durable bag-frame, and finally a bag or satchel having a detachably arranged toilet case within the bag, which at the wish of the owner, can be quickly removed, when not desired to be put into use.

My invention is illustrated in the accompanying three sheets of drawings, in which I have employed similar letters of reference in each of the several views, to indicate corresponding parts.

In said drawings, Figure 1 is a perspective view of a traveling bag embodying my invention, clearly illustrating the arrangement of the detachable toilet or sample case within the bag. Fig. 2 is a plan of the bag when open, with the toilet case closed, and Fig. 3 is a like view of the bag, with the toilet or sample case opened. Fig. 4 is a plan of the bag, when opened, with the toilet case removed, showing an arrangement of swivel keys to which the toilet case can be secured by means of slotted plates. Fig. 5 is a perspective view of the toilet or sample case when removed from the interior of the bag, clearly illustrating an ar-

rangement of flaps or strips provided with said above mentioned slotted plates for securing said toilet case by means of said swivels in 55 position within the bag. Fig. 6 is an end view of the bag when closed. Fig. 7 is a vertical cross-section of the bag and its toilet case in position, and Fig. 8 is a similar view of the bag, with the toilet case removed, clearly illustrating the workings of the frame of the bag when the latter is opened. Fig. 9 is a top view or plan of the bag-frame. Fig. 10 is a perspective view of a swivel post or key employed in my improved form of bag, and Fig. 65 11 is a perspective view of the slotted plate employed.

The bag A and its frame A' on which my improvement is intended to be used are shown in the drawings and consist of the end pieces 70 a and a' provided on their opposite ends with suitable loops or eyes a² to which are pivoted or jointed the frame-sections a³ and a⁴, as will be clearly seen from Fig. 9. To the end pieces a and a' are secured by means of pins or rivets b', the "tips" or "end tips" b, which are L-shaped in cross-section and form a suitable "shoe" at each end of the jointed or pivoted frame-sections, and which act as protectors 75 against the tearing apart in consequence of 80 the rough handling to which they are subjected on cars and in baggage rooms, and also in a great degree protecting the bag frame at the point desired and also making a strong frame at the joint. 85

Extending longitudinally through the bottom of the bag are two rods or bars a⁵ and a⁶, see Figs. 7, 8 and 9, which are designed to strengthen the frame, and also extend through the lower ends of the frame-sections and form 90 the pins on which said frame sections turn and by which they are pivotally secured to the loops or eyes a² on said end pieces a and a'. This frame is covered in the usual manner with leather and lining thereby forming 95 the bag illustrated more particularly in Figs. 6, 7 and 8.

As will be noticed from Fig. 8, the bag frame being of the peculiar form of construction as just described, when the bag is opened, a 100 raised portion A², will be the result, which for convenience I will call the "base" of the bag. As will be seen from Fig. 4, I have arranged on said base A², at its opposite ends the swivel-

posts or keys c and c' , while on the opposite sides of said base and extending out therefrom, as shown, I have arranged a set of swivel posts or keys d and d' . Within said bag A and upon said swivel posts or keys d and d' , I have removably arranged a sample or toilet case E, which, as will be seen from Figs. 1, 5 and 7, comprises therein two pocket-shaped partitions or compartments e^4 and e^5 , which are pivotally connected or hinged to one another at the bottom to form a complete bag. At their upper edges, said partitions may be provided with any suitable form of locking means e^6 for retaining said bag-portions e^4 and e^5 in their closed relation to one another.

My improved form of sample or toilet case E, which forms a suitable partition within the bag, also forms an additional bag or receptacle into which may be placed wearing apparel, such as linen shirts, to prevent them from becoming soiled and to prevent the starched bosoms of the shirts from becoming broken, as is often the case in bags, as now made. The bottom of this additional bag or case must be of the same width as the base A² and is provided at its opposite ends with the flaps or strips e and e' respectively, provided with the slotted plates f and on the opposite sides of said toilet case, are the longitudinal flaps e^2 and e^3 , provided with the slotted plates f' . Said plates, which are preferably of the construction illustrated in Fig. 11 are secured to said flaps by means of their flanges f^2 between which the leather of the flaps is secured, or they may be fastened to said flaps by means of rivets or pins, or in any other well-known manner. In order to secure said toilet or sample case E, in position within the bag A, it is placed on the base A². The slotted plates f on the flaps e and e' are passed over the swivel-posts or keys c and c' which are turned in holding engagement with said plates f' whereby the toilet case is securely held in place within the bag. Of course, it will be evident, that any desirable number of such swivel posts or slotted plates may be used, but the toilet case may be fastened in any other convenient manner, as for instance, by means of hooks and eyes, or by staples and pins. The advantage in this form of bag is, that in case the owner of the bag does not wish to use the toilet or sample case, it can be removed.

Having thus described my invention, what I claim is—

1. A bag frame, comprising therein, the end pieces a and a' , frame-sections hinged or jointed thereto, rods or bars a^5 and a^6 connecting said hinged or jointed parts of the frame, and plates b secured to said end pieces a and a' , substantially as and for the purposes set forth.

2. In a bag or the like, the combination, with the frame thereof, of a sample or toilet case, comprising therein two pocket-shaped

partitions pivotally connected at their bottoms, to form an additional bag, having flaps at their sides, and means for detachably securing said toilet case to said frame, substantially as and for the purposes set forth. 70

3. In a bag or the like, the combination, with the frame thereof, of a sample or toilet case, comprising therein two pocket-shaped partitions pivotally connected at their bottoms, to form an additional bag, having flaps at their sides, slotted plates on said flaps, and swivel posts or keys on said frame, adapted to be engaged and locked with said slotted plates, substantially as and for the purposes 80 set forth.

4. In a bag or the like, the combination, with the frame thereof, comprising therein, the end pieces a and a' and the frame-sections hinged thereto, of a toilet case or sample 85 case, comprising therein two pocket-shaped partitions pivotally connected at their bottoms, forming an additional bag, provided with flaps forming hinge-pieces, and means for detachably securing said parts to said frame, 90 substantially as and for the purposes set forth.

5. In a bag or the like, the combination, with the frame thereof, comprising therein, the end pieces a and a' , frame-sections hinged or jointed thereto, and plates b secured to said 95 end pieces a and a' , of a sample or toilet case, comprising therein two pocket-shaped partitions pivotally connected at their bottoms, to form an additional bag, provided with flaps forming hinge-pieces, and means for detachably securing said parts to said frame, 100 substantially as and for the purposes set forth.

6. In a bag or the like, the combination, with the frame thereof, comprising therein, the end pieces a and a' , frame sections hinged 105 or jointed thereto, rods or bars a^5 and a^6 connecting said hinged or jointed parts of the frame, and plates b secured to said end pieces a and a' , of a sample or toilet case, comprising therein two pocket-shaped partitions pivotally connected at their bottoms, to form an 110 additional bag, provided with flaps forming hinge-pieces, and means for detachably securing said parts to said frame, substantially as and for the purposes set forth. 115

7. In a bag or the like, the combination, with the frame thereof, comprising therein the end pieces a and a' , frame sections hinged or jointed thereto, rods or bars a^5 and a^6 connecting said hinged or jointed portions of the frame, and swivel posts or keys d and d' , of a sample or toilet case, comprising therein two pocket-shaped partitions pivotally connected at their bottoms, to form an additional bag, provided with flaps e^2 and e^3 forming hinge- 120 pieces, and slotted plates f' on said flaps, with which said swivel posts or keys d and d' are adapted to engage and lock, substantially as and for the purposes set forth. 125

8. In a bag or the like, the combination, 130 with the frame thereof, comprising therein the end pieces a and a' , frame-sections, hinged

or jointed thereto, rods or bars a^5 and a^6 connecting said hinged or jointed portions of the frame, and swivel posts or keys d and d' , and c and c' , of a toilet case or partition provided
5 with flaps e^2 and e^3 forming hinge-pieces, and slotted plates f on said flaps, with which said
10 swivel posts or keys d and d' are adapted to engage and lock, flaps e on the ends of said
toilet case or partition, and slotted plates f in
said flaps e , with which said swivel posts or

keys c and c' are adapted to engage and lock, substantially as and for the purposes set forth.

In testimony that I claim the invention set forth above I have hereunto set my hand this 25th day of March, 1893.

ADAM C. KRICK.
